THERMOSTAT MOUNTING

William H. Radford, Peoria, Ill., assignor to
 Caterpillar Tractor Co., San Leandro, Calif., a
 corporation of California

Application November 14, 1932, Serial No. 642,516

4 Claims. (Cl. 236—34)

5 My invention relates particularly to the means for disposing a thermostat unit in the water system of an internal combustion engine. This application is a continuation in part of my copending application, Serial No. 361,423, filed May 8, 1929.

10 An object of my invention is to provide a thermostat mounting of such a character that the thermostat can easily be inserted into position and removed therefrom.

15 Another object of my invention is to provide an inexpensive mounting for a thermostat.

Another object of my invention is to simplify the assembly of a thermostat unit in a cooling system.

The foregoing and other objects are attained in the embodiment of the invention shown in the drawings, in which:

Description of figures

20 Fig. 1 is a side elevation of a portion of a tractor in which the thermostat mounting of my invention is employed, with certain parts in cross section on a vertical longitudinal plane.

25 Fig. 2 is a cross section on the line 2—2 of Fig. 1.

Fig. 3 is a cross section on the line 3—3 of Fig. 2.

30 Fig. 4 is a fragmentary elevation, partly in section, illustrating a modified form of construction.

General description of invention

In general terms, the construction of my invention comprises a water duct or passage which connects an engine, such as an internal combustion engine, to the header or top tank of a radiator employed in combination with the engine. The passage is formed with a chamber portion adapted to receive a thermostat unit to be mounted in the chamber; and the chamber is positioned adjacent the end of a detachably secured pipe forming a part of the passage. Thus, the thermostat unit can be readily inserted at the point of connection of the pipe, and it can be maintained in place by virtue of said connection. A restricted portion or abutment is formed in the passage, against which abutment the thermostat unit is held preferably by means of a spring. The spring is preferred, because it will effect self-ejection of the thermostat unit when it is desired to disconnect the pipe for removal of the unit.

Detailed description—Figures 1-3

55 Reference will now be made to the drawings

for a more detailed description of my invention. Figs. 1 through 3 illustrate the invention as it is incorporated in a tractor. This vehicle includes an internal combustion engine 6 having a water cooling radiator 7. The lower tank or header 8 of the radiator connects through a conduit 9 with a water pump 11 on the shaft, to which a cooling fan 12 is fastened. Water discharged from the engine 6 passes through a pipe 13 detachably secured to the engine by screws 14, and enters a chamber 15 in the upper radiator tank or header 17. Pipe 13 and chamber 15 thus form a water conducting passage, connecting the engine with the radiator; chamber 15 being in said passage.

In accordance with my invention, the chamber 15 is preferably pierced on one side by an aperture 18 disposed opposite the upper wall 19 of the header. A thermostat unit, comprising a cage generally designated as 21, is situated within chamber 15. The unit includes a collar 22 of 20 such a diameter as to pass freely through aperture 18, and on which are mounted uprights 23. Cross members 24 span the uprights and confine an expansible metal bellows 26. Secured to the bellows and moved thereby is a valve 27 adapted 25 to seat on the walls of a port 28 formed in collar 22. When the water, being pumped to the radiator by pump 11, rises in temperature, the bellows 26 expands and dislodges valve 27 from its seat permitting circulation through the chamber 15 and throughout the cooling system of the engine 6. Upon a drop in temperature of the cooling water below a predetermined amount, the bellows 26 contracts thereby seating valve 27 and diminishing or stopping completely the 30 circulation of water in the cooling system.

In order to mount the thermostat unit within chamber 15, I preferably situate the collar 22 just within the aperture 18 and oppose the collar with a coil spring 29 contacting against a spring 40 seat 31 provided in the top wall 19 of the chamber 15. The spring 29 tends to urge the thermostat cage out of the chamber 15. In order to maintain the thermostat cage in proper position, I form pipe 13 with an upper flanged end 32 45 which is detachably secured to the header 19 by screws 33. The inner diameter of pipe 13 adjacent the header 19 is preferably sufficiently small to provide an abutment against which collar 22 of the thermostat cage is held by the spring. It 50 is thus seen that spring 29 urges the collar against the abutment flange 32 and retains the thermostat unit in position. Upon screws 33 and 14 being removed and pipe 13 retracted, the spring 29 forces the thermostat unit out of chamber 15 55

through aperture 18 and facilitates its ready removal.

Figure 4

Fig. 4 illustrates a modified form of construction. The thermostat unit 421 is generally the same as that described with respect to Figs. 1 through 3; it includes the cage which supports collar 422, expansible bellows 426 and valve 427 movable by the bellows. However, in contradistinction to the construction illustrated in Figs. 1 through 3, valve 427 has a flat planar surface adapted to engage the under surface of collar 422, which under surface forms a seat for valve 427. A small aperture 428 is formed in valve 427 to allow a slight flow of water to the bellows 426. Thus, bellows 426 can expand and contract by virtue of direct contact with water from the engine, instead of by heat conductivity. This makes for more responsive action than is the case with respect to the modifications of Figs. 1 through 3.

Instead of mounting the thermostat unit in a chamber formed in the upper header or tank of the radiator, as is the case with respect to the previously described modification, the thermostat unit is positioned in chamber 431 formed at the end of pipe 432 adjacent engine 433. Pipe 432 is detachably secured, at one end, by screws 434 to the upper header or tank 436 forming part of radiator 437. At its opposite end, pipe 432 is detachably secured by screws 438 to outlet 439, which communicates with the water jacket of engine 433.

From the preceding description, it is apparent that outlet 439, pipe 432 including chamber 431 and header 436 form a passage for the conduction of water from the engine to the radiator; and that the thermostat unit is mounted in chamber 431 of the passage. Collar 422 of the thermostat unit fits within aperture 441 in the lower end of chamber 431; and it is held against the top 442 of outlet 439, by means of spring 443. Top 442 of outlet 439, as can be seen from Fig. 4, projects inwardly of aperture 441 to provide the abutment in the water-conducting passage, against which abutment collar 422 is pressed. The top of spring 443 bears against cover 444 detachably secured over chamber 431, by means of screws 446.

The construction of Fig. 4 permits removal of the thermostat unit, when this is desired, either by taking off cover 444 and lifting the thermostat unit through the top of chamber 431, or by removing pipe 432. In the latter case, spring 443 will act to eject the thermostat unit from chamber 431.

Conclusion

In both the described modifications, it can be seen that because the thermostat unit is positioned adjacent the point of connection of the detachably secured pipe, a simple and compact construction obtains, which construction permits facile installation or removal of the unit. Because of the compactness and simplicity of the thermostat unit per se, installation and removal thereof is also enhanced, inasmuch as it is unnecessary to connect or disconnect elements which make up part of the temperature control means.

I, therefore, claim as my invention:

1. In a cooling system for an internal combustion engine; a radiator; a passage for circulation of water from said engine to said radiator; said passage including a plurality of hollow members detachably secured together in abutting relationship, the wall of one of said members adjacent the point of connection having a portion projecting inwardly of said passage to provide an abutment; a thermostat unit having a valve seat adapted to be held against said abutment; and means for holding said valve seat against said abutment.

2. In a cooling system for an internal combustion engine; a radiator; a passage for circulation of water from said engine to said radiator; said passage including a plurality of hollow members detachably secured together in abutting relationship, the wall of one of said members adjacent the point of connection having a portion projecting inwardly of said passage to provide an abutment; a thermostat unit in another of said members and having a valve seat adapted to be thrust against said abutment; and a coiled spring compressed in said another of said members and bearing against said valve seat to hold resiliently said valve seat against said abutment.

3. A cooling system for an internal combustion engine comprising a radiator, a passage from said engine to said radiator, a second passage from said engine to said radiator, said passages cooperating to provide for circulation of cooling fluid between said engine and said radiator, one of said passages having a chamber therein and including a detachably secured duct member, the chamber being positioned adjacent a point of connection of said duct member, a thermostat control unit positioned in said chamber adjacent said point of connection of said duct member and including a valve seat member extending across said one passage, and means independent of the securing means for said duct member for holding said valve seat member against an annular abutment in said one passage.

4. A cooling system for an internal combustion engine comprising a radiator; a passage from said engine to said radiator; a second passage from said engine to said radiator; said passages cooperating to provide for circulation of cooling fluid between said engine and said radiator; one of said passages having a chamber therein and including a detachably secured duct member; the chamber being positioned adjacent a point of connection of said duct member; a thermostat control unit in said chamber and comprising a valve seat member extending across said one passage adjacent the point of connection of said duct member, a thermostat, means supporting said thermostat on said valve seat member, a valve adapted to seat on said valve seat member, and a valve stem connecting the valve to said thermostat; and means, independent of the securing means for said duct member, engaging said valve seat member for retaining said thermostat unit in position, with said valve seat member against an annular abutment in said one passage.

WILLIAM H. RADFORD.
